UNITED STATES PATENT OFFICE.

HAMILTON E. SMITH, OF WEST FITCHBURG, MASSACHUSETTS.

DESIGN FOR CRANK.

Specification forming part of Design No. 7,204, dated February 24, 1874; application filed February 12, 1874.
[Term of Patent 14 years.]

To all whom it may concern:

Be it known that I, HAMILTON E. SMITH, of West Fitchburg, in the county of Worcester and State of Massachusetts, have invented a new and original Design for Crank; and I do hereby declare the following to be a full, clear, and exact description thereof, which will enable those skilled in the art to make and use the same, reference being had to the accompanying drawing, forming part of this specification, in which drawing—

Figure 1 represents a front view of my crank. Fig. 2 is a transverse section of the same.

Similar letters indicate corresponding parts.

This invention relates to a design for a crank, the shank of which is tapering from the hub to the handle, and ornamented by two raised ribs extending along its edges, while the web, which forms the junction between said raised ribs, is perforated with holes of a gradually-decreasing size, thus producing a crank which has a novel and ornamental appearance.

In the drawing, the letter A designates a crank, the shank of which is tapering from the hub B toward the handle C. Said shank is ornamented by two raised ribs, *a a*, which extend along its edges, and the web *b*, which intervenes between said ribs, is perforated with a series of holes, *c*, of gradually-decreasing diameter, and by these means a crank is produced which has a distinguishing and ornamental appearance.

What I claim as new, and desire to secure by Letters Patent, is—

The design for a crank, consisting of a tapering shank with raised ribs *a a* and a web, *b*, perforated with holes *c* of gradually-diminishing diameter, as shown and described.

HAMILTON E. SMITH.
